CLAIM

The ornamental design for a laboratory device, as shown and described.

DESCRIPTION

FIG. 1 is a front perspective of a first embodiment of a laboratory device, with a lid thereof in an open configuration showing a condenser, and microscope stage;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan thereof;

FIG. 7 is a bottom plan thereof;

FIG. 8 is a front perspective of a second embodiment of a laboratory device, with a lid thereof in an open configuration showing a microscope stage;

FIG. 9 is a front elevation view thereof;

FIG. 10 is a rear elevation view thereof;

FIG. 11 is a right elevation view thereof;

FIG. 12 is a left elevation view thereof;

FIG. 13 is a top plan thereof;

FIG. 14 is a bottom plan thereof;

FIG. 15 is a front perspective of a third embodiment of a laboratory device, with a lid thereof in an open configuration showing a condenser;

FIG. 16 is a front elevation view thereof;

FIG. 17 is a rear elevation view thereof;

FIG. 18 is a right elevation view thereof;

FIG. 19 is a left elevation view thereof;

FIG. 20 is a top plan thereof; and,

FIG. 21 is a bottom plan thereof.

The broken lines in the drawings depict portions of the laboratory device that form no part of the claimed design.
